UNITED STATES PATENT OFFICE.

ALEXANDER VAN SLYKE, OF FORT PLAIN, NEW YORK, ASSIGNOR TO
ELEANOR EHLE, OF SAME PLACE, AND WALTER LIPE, OF NEW
YORK, N. Y.

CHAIR.

SPECIFICATION forming part of Letters Patent No. 433,836, dated August 5, 1890.

Application filed February 11, 1890. Serial No. 339,991. (No model.)

To all whom it may concern:

Be it known that I, ALEXANDER VAN SLYKE, a citizen of the United States, residing at Fort Plain, in the county of Montgomery and

5 State of New York, have invented a certain new and useful Improvement in Chairs, of which the following is a full, clear, and exact description.

This invention relates to convertible rock-
10 ing and reclining chairs.

The invention comprises a platform rock-
15 ing-chair, the bottom of the seat portion of
which is adapted to rest and rock upon a sta-
tionary platform, the back of the chair being
hinged to the seat and provided with arms,
20 which are adjustably connected at their for-
ward ends to the seat portion by a peculiar
and novel catch, whereby the rocking-chair
may be converted into a reclining-chair.
25 The chair is also provided with a movable
foot-rest.

The invention consists in a chair con-
25 structed and arranged substantially as I will
proceed now to set forth, and particularly
claim.

In the accompanying drawings, in the sev-
eral figures of which like parts are similarly
designated, Figure 1 is a perspective view of
the chair. Fig. 2 is a perspective view of the
30 serrated plate of the catch. Fig. 3 is a ver-
tical sectional elevation of the catch com-
plete; and Fig. 4 is a vertical section of one
side of the chair, taken in the plane of line
xx, Fig. 1. Fig. 5 is a vertical section. Fig.
35 6 is a bottom plan view of the foot-rest de-
tached and unfolded, and Fig. 7 is a vertical
cross-section of the said foot-rest folded.

The base or platform of the chair is com-
40 posed of side pieces a, which are united by
rungs or stretchers b, provided, if desired,
with casters c at front and with flat feet d at
rear. These side pieces are curved on their
upper surfaces to form rockers, upon which
45 the seat e rocks. The bottom of the seat is
made with flat rails f, which are fitted to the
sides a in any suitable manner—as, for ex-
ample, by rounding the upper surfaces of the
sides and grooving the adjacent surfaces of
50 the rails f. Any suitable device may be used
for connecting the seat to the platform—as,

for example, the ordinary springs in common
use. The invention, however, is not limited
to the construction of the rocking portions
just described.

The back g of the chair is hinged at h to
the seat. Arms i are pivoted at 2 to the back,
each of which is made as an integer by pref-
erence. Catches j are employed to connect
the arms with the seat at the lower forward
portions of the arms. Each catch is con-
60 structed substantially as follows, (see Figs. 2
and 3:) A tubular sleeve k is inserted in a
hole in the arm and secured therein by means
of the flange l, having screw-holes in it. A
telescoping sleeve m, similarly flanged, is in-
65 serted from underneath the arm and pro-
jected upwardly into the sleeve k. These
telescoping sleeves provide for the applica-
tion of the catch to arms of different vertical
thickness. A coiled spring n is arranged 70
within the sleeve and surrounds a bolt o, and
is made fast to one end of said bolt, so as to
normally throw the bolt upwardly. The
lower end of the bolt is made with a cross-
head p, and the upper end is adapted to re-
75 ceive a thumb piece or button q. The cross-
head p is arranged outside of the lower
sleeve m.

In the frame of the seat is arranged a catch-
80 plate r, having a series of teeth s pointing
downwardly, and these teeth are normally en-
gaged by the cross-head p. By depressing the
bolt the cross-head is disengaged from the
teeth, and thus the arms of the chair, and con-
sequently the back, are free to be adjusted to
85 change the inclination of the back. As soon
as pressure upon the bolt is released its spring
n carries the cross-head p back into engage-
ment with the serrated plate r. It will be no-
ticed that by the employment of this sort of
90 catch the arms of the chair need not be di-
vided, and hence their symmetry is preserved
and the operation of inclining the back greatly
facilitated.

A foot-rest of suitable construction is ap-
95 plied to the chair, and the preferred form of
foot-rest consists of a rest or board t', suitably
upholstered, if desired, and provided with
ratchet-faced lugs t² at one end, which form
halves of hinges, by which the rest is adjust-
100

ably secured to the chair. The other halves of these hinges are made as rails v , which terminate in ratchet-faces v' to match and register with the ratchet-faced lugs t^2 t^2 , the two pairs of hinges being connected by a spring-bolt w , which may be passed freely through the parts v' v' and be fixed to the parts t^2 t^2 , so that when moved longitudinally the said rod will move the parts t^2 t^2 from the parts v' v' —that is to say, separate their teeth—and thereby permit the movement of the board or rest t' in a direction opposed to the engaging faces of the ratchet-teeth, so as to admit of the adjustment of the board or rest in a direction upward, as indicated by arrow 3, or downward and backward, as indicated by arrow 4 in Fig. 5, the release of the spring-bolt enabling it to return automatically the ratchet-faces into engagement to lock and hold the rest in the adjusted position. The spring-bolt w , however, need not be fixed to the parts t^2 t^2 , but may pass freely through them, and pressure upon the rest or board may be exerted to separate the parts t^2 t^2 and v' v' for purposes of adjustment.

The rails v v are fitted to slide longitudinally in guides v^2 v^2 , which are fixed to the bottom of the chair-seat, and the said rails, having fitted to them, as described, the rest, and being movable, as specified, admit of the projection of the rest forward of the chair, and also admit of the stowing away of such rest when folded back beneath the chair-seat, so as to permit the free use of the chair as a rocking-chair; but the hinge members v' v' may be stationary upon the chair-seat.

The lugs t^2 may be made with the bars t^3 ,

having ears t^4 , by which to secure them with screws or other fastenings to the board or rest t' , and these bars serve also to batten or brace the rest or board.

What I claim is—

1. A chair having a seat and base, a back pivoted to the seat, arms pivoted to the back, and catches interposed between the arms and the seat and composed of telescoping sleeves fitted to the arms, spring-bolts arranged in said sleeves, and serrated plates arranged in the seat and adapted to be engaged by the bolts to permit the adjustment of the back, substantially as described.

2. A foot-rest for chairs, consisting of a rest or board having ratchet-faced hinge members, combined with rails adapted to be fitted to the chair-bottom and provided with counterparts of the said ratchet-faced hinge members, and a spring-bolt connecting the several ratchet-faced members in pairs and normally holding them in engagement and permitting their ready disengagement, substantially as described.

3. A board or rest provided with ratchet-faced hinge members, combined with complementary ratchet-faced hinge members having rails fitted to slide beneath the chair and a spring-bolt uniting the hinge members in pairs and providing for the adjustment of the board or rest, substantially as described.

In testimony whereof I have hereunto set my hand this 5th day of February, A.D. 1890.

ALEXANDER VAN SLYKE.
